Jas. B. Hardin *Michael Thornton*

United States Patent Office.

MICHAEL THORNTON, OF PHILADELPHIA, PENNSYLVANIA.

Design No. 3,530, dated June 1, 1869; reissue No. 3,641, dated September 14, 1869.

DESIGN FOR THE SOLE OF A BOOT OR SHOE.

The Schedule referred to in these Letters Patent and making part of the same.

To all whom it may concern:

Be it known that I, MICHAEL THORNTON, of Philadelphia, county of Philadelphia; State of Pennsylvania, have originated a new Design for the Sole of a Boot or Shoe; and I do hereby declare that the accompanying drawing and the following explanation thereof form a full, clear, and exact description of the said design.

In the drawing—

Figure 1 is a side view of the sole of a boot or shoe, and

Figure 2, a transverse section of the sole, on which

are formed three ribs, a, b, and c, in the manner clearly illustrated in the drawing.

These ribs and intervening grooves impart a light appearance to a thick sole.

I claim the design for the sole of a boot or shoe, substantially as described, and as represented, in and by the accompanying drawing.

In testimony whereof, I have signed my name to this specification, before two subscribing witnesses.

Witnesses: MICHAEL THORNTON,
JOHN WHITE,
HARRY SMITH.
